CLAIM

The ornamental design for a combined paint container and lid therefor, as shown and described.

DESCRIPTION

FIG. 1 is a perspective view of a combined paint container and lid therefor showing our new design;

FIG. 2 is a top plan view thereof;

FIG. 3 is a side elevational view, the undisclosed sides being mirror images thereof; and

FIG. 4 is a bottom plan view thereof.

F / G. 1

FIG. 4

FIG. 2

FIG. 3
